ROTARY PUMP

Henry F. Martin, Detroit, Mich., assignor of one-tenth to Charles E. Wisner, and forty-five one-hundredths to Raymond J. Silden, both of Detroit, Mich.

Application April 21, 1934, Serial No. 721,659

5 Claims. (Cl. 103—136)

This invention relates to rotary pumps and the object of the invention is to provide a rotary pump including a rotor carrying a series of rollers riding in contact with the stator and in which the 5 rollers are supported on floating cam members positioned in the housing.

Another object of the invention is to provide a rotary pump comprising a rotor provided with a series of radial slots in which the rollers are 10 positioned, the inner rollers being supported on floating cam members in the pump housing whereby the outer rollers are maintained in contact with the stator.

Another object of the invention is to provide 15 a rotary pump including a rotor having radial slots in which the rollers are loosely positioned, the inner rollers in each slot being provided with sloping faces and a pair of floating cam members being positioned on opposite sides of the rotor 20 between the sloping ends of the inner rollers and provided with sloping faces on which the inner rollers are adapted to ride during rotation of the rotor to support and maintain the outer rollers in contact with the stator.

Another object of the invention is to provide 25 a rotary pump of the character described in which the floating cam members are provided with sloping conical faces whereby the cam members may be adjusted toward each other to move 30 the rollers outwardly and take up wear.

These objects and the several novel features 35 of the invention are hereinafter more fully described and claimed and the preferred form of construction by which these objects are attained is shown in the accompanying drawings in which—

Fig. 1 is a sectional view of a rotary pump embodying my invention, the rollers, rotor and floating cams being shown in elevation.

Fig. 2 is a section taken on line 2—2 of Fig. 1. Fig. 3 is a view similar to Fig. 1 showing the rotor in a different position.

Fig. 4 is a section through a multiple roller pump.

Fig. 5 is a section taken on line 5—5 of Fig. 4. Fig. 6 is a section through an alternative and probably the simplest form of the pump.

Fig. 7 is a section taken on line 7—7 of Fig. 6.

The pump, as shown in Figs. 1 and 2, comprises 50 a stator 1 mounted on a base 2. This stator 1 is provided with an inlet chamber 3 and an outlet chamber 4 and an inlet pipe may be threaded into the aperture 5 leading into the chamber 3 while an outlet pipe may be threaded into the 55 aperture 6 leading from the outlet chamber 4.

A cylindrical lining 7 is fixedly mounted in the stator 1 and is provided with an opening 8 registering with the inlet chamber 3 and with an opening 9 registering with the outlet chamber 4. The rotor, as shown more particularly in Fig. 1, 5 comprises an outer annular portion 10 of the full width of the central pump chamber as shown in Fig. 2 and a concentric recess 11 is formed in one side thereof while a similar concentric recess 12 is formed in the other side thereof.

The rotor thus formed is provided with a series 10 of three radial slots 13 and each radial slot is provided with an outer roller 14 and with an inner roller 15 which rollers are loosely positioned in the radial slots 13. A metal cam ring 16 is 15 positioned in the recess 11 in the rotor between the ends of the three rollers 15, as shown in Fig. 1. A similar metal ring 17 is positioned in the recess 12 between the opposite ends of the three rollers 15. These rings 16 and 17 are freely 20 mounted between the ends of the three rollers 15 and these rings are provided with sloping outer faces while the rollers 15 may also be provided with companion sloping faces at the ends to rest on the rings 16 and 17, as shown in Fig. 2. 25

The drive shaft 18 for the pump extends through the center of the rotor and is secured thereto by a key 19. This shaft is rotatably mounted in a bushing 20 provided in the cover member 21 and in a bushing 22 provided in the extension 23 of the housing 1. This shaft is also provided with a collar 24 and a spring 25 is positioned behind the collar and is retained in place by a plug 26 threaded into the end of the extension 23. 30

In operation, the shaft 18 is rotated to rotate the rotor. This rotor carries the rollers 14 and 15 around therewith in the slots 13 as will be readily understood from Figs. 1 and 3. The rotor is rotated in a counter-clockwise direction and 40 by the eccentric position of the rotor in relation to the stator fluid is drawn from the inlet chamber 3 into the chambers between the successive rollers 14 and is carried around to the discharge or outlet chamber 4 and discharged.

The various positions of the rotor will be understood more particularly from Figs. 1 and 3 and it will be noted that due to the floating cam rings 16 and 17 the rollers are always maintained in contact with the stator due to the fact that 50 the rollers 15 continuously ride on the outer surface of the cam rings 16 and 17. Due to the sloping faces of the cam rings, the rollers 15 will automatically adjust themselves to proper position in maintaining the rollers 14 in contact with 55

the stator. The pump will also operate in a reverse direction in which case the chamber 4 becomes the inlet chamber and the chamber 3 becomes the discharge chamber.

By providing two rollers, as shown in Figs. 1 and 3, the rollers 15 will rotate in a counter-clockwise direction while the rollers 14 will rotate in a clockwise direction. This is due to the fact that the rollers 15 are riding on the cam rings 16 and 17 and the rollers 14 are riding on the inner face of the stator so that there is no wear between the rollers 14 and the stator and no wear between the rollers 15 and the cam rings 16 and 17 and if the rollers are of approximately the same diameter there is no appreciable slippage between the rollers and consequently no wear between the rollers and thus the only wear on the rollers would be where the rollers contact the faces of the slots 13 in the rotor.

An alternative form of construction is shown in Figs. 4 and 5 in which two outer rollers 27 are provided and supported on an inner roller 28, the rollers being positioned in an enlarged radial slot in the rotor. The rollers 28 are supported on two floating cones 29 and 30 and the rotor is provided with an extension 31 which is secured to the shaft 32 by means of the key 33. In this construction the cones 29 and 30 are mounted in the central opening of the rotor between the three inner rollers 28 and the rollers 28 maintain each pair of rollers 27 in contact with the inner face of the stator so that a double seal is provided adjacent each rotor slot. These cones are here termed "floating cones" due to the fact that they are moved concentrically about the axis of the stator through the varied position of the rollers during rotation of the rotor and thus in a sense are floating and are not axially fixed. Due to the difference in angular position of the stator face in relation to the outer circumference of the rotor the rollers 27 may compensate in angular position for this variation. For instance, at the top of Fig. 4 both rollers 27 are in approximately the same angular position in relation to the roller 28. In the position shown at the left of Fig. 4, the roller 27a is advanced beyond the roller 27b and in the position shown at the right of Fig. 4 the roller 27b extends outwardly beyond the roller 27a. With this arrangement shown in Fig. 4, the rollers may therefore compensate and accommodate themselves to the stator face and, at the same time, provide a double seal.

As will be noted from Fig. 5, a shoe 34 is provided to which a screw shaft 35 is secured and this screw shaft is threaded through the portion 36 of the cover 37 and is provided with a lock nut 38. By removing the cap 39, the lock nut 38 may be released to allow the screw 35 to be threaded inwardly to force the cone 29 toward the cone 30. This will spread the rollers 28 apart and force the rollers 27 outwardly and provides a means for taking up wear of the rollers 27 or 28 or wear on the cones 29 and 30. After the screw 35 has been properly adjusted, the lock nut 38 may be again tightened.

An alternative form of the pump is shown in Figs. 6 and 7 which is probably the simplest form of the pump. In this form, the housing 40 is provided with bushings 41 and 42 for the shaft 43. This shaft 43 extends through these bushings and is secured to the hub 44 of the rotor by a key 45. This rotor is provided with an integral portion extending into the stator chamber and having three radial slots for the rollers 47 leaving three driving portions 48. The portions

48 are arranged on a circle eccentric to the cylindrical pump liner 49 and the rollers 47 are arranged to ride in contact with the inner cylindrical face of the pump liner 49. In order to maintain the rollers 47 in contact with the liner 49, a fourth roller 50 is positioned between the three rollers 47 and this fourth roller is free so that it will automatically seek a position centrally of the three rollers 47.

The inlet conduit 51 opens into the inlet chamber 52 and this chamber opens into the interior of the pump through the port 53 while the discharge port 54 opens from the opposite side of the pump into the discharge chamber 55 and, in this case, the rotor rotates in a counter-clockwise direction. If the pump is arranged for the rotor to rotate in a clockwise direction, the inlet and discharge ports are reversed.

The operation of the device will be more readily understood from Fig. 7 in which the rotor comprising the three portions 48 is rotated in a counter-clockwise direction. As the rotor rotates, the three rollers 47 roll on the inner cylindrical face of the pump liner 49 and as these three rollers are all of the same diameter, the compensating roller 50 will rotate in the opposite direction so that there is no friction between the rollers. It will be noted that the roller 50 automatically assumes a position eccentric to the center of the shaft 43 but centrally of the cylindrical stator liner 49 and in this position maintains the three rollers 47 at all times in contact with the inner cylindrical face of the pump liner 49. By this arrangement, the fluid is drawn from the inlet port 53 and is carried around the right side of the rotor and is forced out through the discharge port 54. In this pump, all four rollers 47 and 50 rotate freely and, at the same time, have maximum effectiveness in pumping. Should the rollers become worn, the cap 56 may be removed from the pump by removing the bolts 57 and the roller 50 may be removed and may be replaced by a roller of slightly greater diameter to take up the wear.

From the foregoing description it becomes evident that the device is very simple and efficient in operation, will not easily get out of order, is composed of few parts and is of consequent low manufacturing cost and provides a device which accomplishes the objects described.

Having thus fully described my invention, its utility and mode of operation, what I claim and desire to secure by Letters Patent of the United States is—

1. In a rotary pump, a stator provided with an interior cylindrical face and having inlet and exhaust ports, a rotor rotatably mounted in the stator, the rotor being spaced from the cylindrical face of the stator through a portion of its circumference, a pair of conical members positioned within the stator chamber and each having a circular conical face, the rotor being provided with a series of radial slots, a plurality of rollers positioned in each radial slot, the inner roller in each slot being provided with conical ends resting on the conical members, said conical members being independently supported in position by the respective conical ends of the inner roller permitting disalignment of the axes of the conical members to compensate for imperfections in construction and wear, means for adjusting one of the conical members axially and a shaft for driving the rotor.

2. In a rotary pump, a stator provided with an interior cylindrical face and having inlet and

5 exhaust ports, a rotor rotatably mounted in the stator, the rotor being spaced from the cylindrical face of the stator through a portion of its circumference, a pair of conical members freely mounted in the stator, the rotor being provided with a series of radial slots opening through the outer face thereof, a plurality of rollers positioned in each radial slot, the inner roller in each slot riding on the conical members, said 10 conical members being independently supported in position by the respective conical ends of the inner roller permitting disalignment of the axes of the conical members to compensate for imperfections in construction and wear, means for adjusting one of the conical members toward the other and means for driving the rotor.

20 3. In a rotary pump, a stator provided with an interior cylindrical face and having inlet and exhaust ports, a rotor rotatably mounted in the stator, the rotor being spaced from the cylindrical face of the stator through a portion of its circumference, a pair of independently floating conical members, the rotor being provided with a series of radial slots opening through the outer 25 face thereof, a plurality of rollers positioned in each radial slot, the inner roller in each slot

being provided with conical faces riding on the conical members and means for driving the rotor.

4. In a rotary pump, a stator having inlet and exhaust ports and provided with an interior cylindrical face, a rotor rotatably mounted in the 5 stator, the rotor being spaced from the cylindrical face of the stator through a portion of its circumference, a compensating roller positioned on each side of the rotor, the rotor being provided with a series of radial slots opening through the outer face thereof, a plurality of rollers positioned in each slot, at least two of the rollers in each slot riding in engagement with the cylindrical face of the stator and the inner roller in each slot riding on said compensating 10 rollers, and means for driving the rotor.

5. In a rotary pump, a stator, a rotor mounted eccentrically in the stator, the rotor being provided with a series of radial slots, a series of rollers positioned in each slot, at least two of the 20 rollers of each series contacting the stator face, and a compensating roller mounted centrally of the series of rollers and arranged so that a roller of each series of rollers rides on the compensating roller.

HENRY F. MARTIN.
